UNITED STATES PATENT OFFICE.

CLEOPHAS GAMACHE, OF BARRE, VERMONT, ASSIGNOR OF ONE-HALF TO JOSEPH LADRIE, OF BARRE, VERMONT.

WINDOW-HEATER.

1,285,114.

Specification of Letters Patent. Patented Nov. 19, 1918.

Application filed November 5, 1917. Serial No. 200,411.

To all whom it may concern:

Be it known that I, CLEOPHAS GAMACHE, a subject of the King of Great Britain, residing at Barre, in the county of Washington and State of Vermont, have invented 5 certain new and useful Improvements in Window-Heaters, of which the following is a specification.

The principal object of the invention is to 10 provide a heater which can be used in connection with a window sash for heating space between the double glasses of the sash thus preventing snow or ice from collecting upon the glass.

Another object of the invention is to so 15 construct this heater that it will not interfere with the opening or closing of the window.

Another object of the invention is to so 20 construct the heater that it may be protected and further to so construct it that it will take up a minimum amount of room.

This invention is illustrated in the accompanying drawings, wherein:—

25 Figure 1 is a view in elevation showing a window provided with the improved heater,

Fig. 2 is a vertical sectional view taken along the line 2—2 of Fig. 1,

Fig. 3 is a sectional view taken along the 30 line 3—3 of Fig. 1, and

Fig. 4 is a view similar to Fig. 1 showing a modified construction.

The window sash 10 is slidably mounted in the window frame 11 and may have either 35 vertical or transverse sliding movement according to whether the sash is mounted as shown in Fig. 1 or as shown in Fig. 4. This sash will be provided with doubled plates of glass 12 positioned in spaced relation as 40 shown in Fig. 3 and in Fig. 2 and the lower bar 13 and as in Fig. 4, the side bar 14 will be provided with an opening 15 through which the heater housing 16 may pass. This

heater housing is mounted either in the sill 17 or in the side portion of the frame 11 45 and extends outwardly for passing through the opening 15 when the window is closed thus permitting the heat from the heating element 18 to warm the air in the space between the plates of glass 12 and thus prevent 50 ice and snow from gathering upon the window. This housing is provided with an opening 19 for permitting heating of the air between the glasses 12, it being understood that as many openings as may be desired may be formed. In the present form, the heater has been shown as one or more electric bulbs but it is understood that this simply shows a conventional form of heating 55 medium and that any form of heating element may be substituted for the one shown, and may be energized either by electricity or may be of a different type, such for instance as steam, hot water or hot air or gas.

Having thus fully described my invention, what I claim as new and desire to protect by Letters Patent is:—

A structure of the character described comprising a window frame, a sash movably mounted in the frame and provided with inner and outer panes positioned in spaced relation, the sash being provided with an opening permitting communication with the space between the panes, and a heating medium carried by the frame and extending through the opening in the sash into the space between the panes when the sash is closed.

In testimony whereof I affix my signature 80 in presence of two witnesses.

CLEOPHAS GAMACHE.
